Lester F. Dillenhofer
ATTORNEY

UNITED STATES PATENT OFFICE.

JOHN HARRINGTON SICKEL, OF SPRING LAKE, NEW JERSEY.

RAILWAY SIGNAL TORPEDO.

Application filed May 27, 1922. Serial No. 564,002.

To all whom it may concern:

Be it known that I, JOHN HARRINGTON SICKEL, a citizen of the United States, residing at Spring Lake, in the county of Monmouth and State of New Jersey, have invented a certain new and useful Improvement in Railway Signal Torpedoes, of which the following is a specification.

This invention relates to improvements in detonating torpedoes of the class used for railway signaling purposes, and particularly to the type in which the explosive charge is held in a non-metallic container provided with flexible metal straps whereby the torpedo may be fastened to a rail in position to be detonated by a wheel of a locomotive or car.

One of the objects of the invention is to provide a non-flying torpedo made of paper or like material which will be completely destroyed or annihilated by the force of the explosion and without producing any flying fragments that might cause injury or damage.

Another object of the invention is to provide a torpedo having a relatively broad, shallow, non-metallic casing of sufficient length to extend transversely across the rail head, the form of the casing being such as to provide a compact torpedo that can be conveniently handled, that affords a broad area of contact with both the rail and the wheel of the locomotive or car so that it will be completely crushed when the wheel passes over it, and in which the force of the explosion is from the sides.

A further object is to provide a torpedo having the ends of the casing strengthened and reenforced with non-metallic caps so as to increase the endwise resistance of the torpedo, whereby to produce a louder detonation, and to concentrate the force of the explosion along the sides of the casing.

A still further object is to provide a construction wherein the metal fastening straps are anchored in the reenforcing caps and are insulated from and do not come into contact with the explosive charge or the casing containing the same.

I attain these objects, as well as others, by means of the construction and arrangement of parts described in the following specification, it being understood that modifications may be made therein without departing from the scope of the invention as defined in the claims.

In the accompanying drawings, illustrating a preferred embodiment of the invention,

Figure 1 is a perspective view of the improved torpedo, 60

Figure 2 is a perspective view of the case that contains the explosive charge, and

Figure 3 is a perspective view of one of the reenforcing end caps, showing the fastening strap anchored therein. 65

Referring now to the drawings, 1 indicates the body portion of the torpedo consisting of a substantially oblong shaped shallow casing made of waterproofed paper, fibre composition, or other suitable non-metallic substance, which case is adapted to contain and encase a charge of detonating powder or composition, and has its ends closed and sealed by means of folded flaps 2, or otherwise, and is of sufficient length to extend 70 transversely across a rail head.

3 indicates the non-metallic reenforcing caps which are preferably made of the same material as the casing. The caps are shaped to fit snugly over the ends of the casing and 80 are crimped or otherwise secured thereto. The caps serve both to strengthen the torpedo and to provide anchorages for the fastening straps 4.

The fastening straps 4 are made of lead, 85 tin or any other suitable metal adapted to be easily bent so as to engage over or grip the rail head and thereby fasten the torpedo in place. An end of each strap is inserted through a slit in the cap and is anchored 90 or secured thereto. As seen in Fig. 3 the anchorage may be easily effected by splitting the inserted end of the strap and bending the split portions in opposite directions.

It will be noted that in my improved torpedo the fastening means do not pass through the case that contains the detonating composition but consists of two separate straps each of which is anchored in one of the caps that fit over an end of the case. 95 Upon detonation of the torpedo the straps will fall harmlessly on the roadbed at either side of the rail.

What I claim is:

1. A railway signal torpedo comprising 105 a broad shallow inclosing case made of non-metallic material and having closed ends, non-metallic caps fitting tightly over the closed ends of the case, and a pair of flexible rail-engaging straps each having an end 110 anchored in one of the caps.

2. A railway signal torpedo comprising

a non-metallic inclosing case having closed ends, non-metallic caps fitting tightly over the closed ends of the case, and flexible rail-engaging straps secured to said caps and extending in opposite directions.

3. A railway signal torpedo comprising a substantially oblong-shaped non-metallic inclosing case having flap closures at either end, non-metallic caps fitting over the ends 10 of the case and crimped thereto, and flexible rail-engaging straps secured to said caps and extending in opposite directions.

4. A railway signal torpedo comprising a paper inclosing case having closed ends, 15 said case having relatively broad parallel top and bottom walls and having relatively narrow parallel side walls, paper caps fitting tightly over the closed ends of the case, and rail-engaging straps secured to said caps.

5. A railway signal torpedo comprising 20 a broad shallow paper inclosing case having flap closures at either end, paper caps fitting over the closed ends of the case and crimped thereto, and a pair of flexible rail engaging straps each having an end anchored in one 25 of the caps.

6. A railway signal torpedo comprising a paper inclosing case, paper caps fitting over the ends of the case and secured thereto, 30 said caps each having a slit for receiving an end of a flexible metal strap, a pair of flexible metal straps each having an end inserted through the slit in the cap, the inner end of the strap being split longitudinally and bent in opposite directions to anchor the 35 strap in the cap.

JOHN HARRINGTON SICKEL.
